FRIEDRICH WAGNER, OF RUSSDORF B/ÖBERFROHNA, GERMANY

DOUBLE-SIDED WARP GOODS

Application filed November 28, 1928, Serial No. 322,398, and in Germany December 3, 1927.

The invention relates to a double-thickness, warp-knitted fabric, which can be simply, rapidly and economically produced. The new fabric is knitted on two banks with 5 two sets of yarns, one set of yarns feeding only to one bank of needles, the other set of yarns feeding only to the other bank of needles, and the two sets of yarns being only interlocked between their courses. 10 For this purpose, each loop is formed of a single thread, but there are always two loops, one of each set of yarns, lying over each other. The threads are always lapped in the same direction. One of the systems 15 only comprises loops on one side of the fabric and the other only loops on the other side. The threads of each system only cross those of the other outside of the needle loops, which results in a reliable securing of 20 the two fabric layers. The new fabrics have the great advantage that the thickness of the threads may be any desired, and yet a relatively thin material is made, because each 25 loop is formed of only one thread, so that the appearance of knots does not result.

The drawings represent in Figures 1 and 2, two forms of the new material in perspective and on an enlarged scale.

The threads 2 form one of the two thread 30 systems, and the threads 4 belong to the other system. The threads 2 comprise only needle loops, which are visible on the rear side of the fabric, and the threads 4 have needle loops only on the front side of the fabric. 35 Behind each loop of a thread 4 lies a loop of a thread 2. On account of the perspective representation in the drawings, the loops 2 are shown alongside the loops 4, for the sake of clarity. But there are never several 40 threads worked into one loop, and especially there is never a thread 2 combined with a thread 4 in one loop. The two systems 2 and 4 are only connected together in that the threads 2 and 4 cross each other out- 45 side of the needle loops by those sections of thread which extend from one needle loop to another. Each system, furthermore, forms a fabric in itself, which can have any desired laying or chain. Fig. 50 1 presents the respective warp yarns trav-

ersed laterally the distance between needles in successive courses. Fig. 2 shows the respective warp yarns traversed the distance of two needles in successive courses. Thus in Fig. 2 the respective yarns skip a needle in 55 lateral traverse between courses. Both embodiments show the respective sets of warp yarns traversed in opposite direction.

I claim as my invention:—

A double-sided warp fabric consisting of 60 a thread system forming loops on one side of the fabric only and running through said loops in one direction, and a second thread system forming loops on the other side of the fabric only and running through its loops 65 in one direction, said thread systems crossing each other only by the thread parts connecting the loops together and the loops of one thread system being arranged before the loops of the other thread system. 70

In testimony whereof I have affixed my signature.

FRIEDRICH WAGNER.
